HEATING AND AIR CIRCULATING APPARATUS

Application filed January 25, 1928, Serial No. 249,299. Renewed December 17, 1930.

This invention relates to heating and ventilating apparatus, particularly to such apparatus for closed bodies on pleasure cars, taxi cabs and motor busses.

5 The essential object is to provide an efficient and compact vehicle heating apparatus. A further object is to provide a fan operated air circulating and heating device in connection with a heating element such as a motor exhaust manifold, in which the fan and driving means therefor is protected against damage by heat from such heating element. A further object is to provide a ventilating 10 and heating apparatus which shall be unitary 15 in character and extremely easy to install.

As shown in the drawings, our device is of two forms, namely: one in which the fan unit is closely associated with the heater unit but mounted in a separate chamber so as to be 20 protected against excessive heat, and another wherein the fan unit is substantially adjacent but separate from the heating element and connected therewith by a tube. Either form 25 of device is well adapted to fit into the usual vehicle body construction without disturbing the parts thereof other than to cut opening for affording the necessary air passage. The features common to both arrangements 30 shown, as well as the distinctions between them, will be more fully discussed in the following detailed description. Further objects of the invention will also appear. The essential characteristics, of the invention are summarized in the claims.

35 In the drawings, Fig. 1 is a transverse fragmentary sectional view of one lower corner of a vehicle body and showing adjacent portions of the side wall and floor. This figure shows the preferred form of heating and ventilating arrangement. Fig. 2 is a substantially central cross sectional view in a plane parallel to the showing of Fig. 1 the air heating and circulating device being viewed from the opposite direction; Fig. 3 is a side elevation of the form of device shown in Fig. 1 broken away to illustrate the construction of the heating element; Fig. 4 is a longitudinal sectional view through a portion of a passenger body, and showing a modified form of our invention in side elevation; Fig. 5 is a sub-

stantially central longitudinal sectional view through the modified form in a plane parallel to that of Fig. 4.

In ventilating the vehicle bodies it is highly desirable to be able to maintain a constant 55 circulation of air through the body at all times. By the use of our invention we are enabled to circulate a large volume of air through the body, either heated or at normal 60 temperature, whether the vehicle is moving or standing. It is also highly desirable to control the flow of air in such manner that the degree of heat imparted to the whole volume of air delivered may be easily varied 65 while maintaining this volume substantially 65 constant for ventilation. Our arrangement is well adapted to effect this.

The problem of overcoming "hot spot" 70 conditions in heating apparatus is considerable. Our device is particularly well arranged in this regard, in fact there is no appreciable localization of heat at any point in the body mainly because of the large volume of air delivered, which necessarily absorbs 75 only a small degree of heat, per unit of air, in order to completely warm the body in a short time.

The arrangement shown in Figs. 1 to 3 comprises an air directing and circulating unit 80 entirely above the floor, including a fan element and an air duct element which are arranged to communicate one with the other through a heating unit placed below the floor, and exclusive of the heater unit selectively. 85 This form will now be described in detail.

In the arrangement shown the air directing and circulating unit comprises a hollow housing section 1 affording an air receiving space 2, adjacent the fan, and, an air discharge space 3. The unit further comprises a separable fan housing section 4 communicating with the space 2. The housing 1 has a floor portion 5 with openings 6 and 7 therethrough. The opening 6 leads from the space 2 into the heater unit housing 10, which is positioned 90 entirely below the vehicle body floor F. The opening 7 affords communication from the housing 10 into the discharge chamber or space 3. The housing 10 contains a suitable heating element, shown as comprising a mani- 95

fold of pipes 11 which form a part of the exhaust line for conducting exhaust gases from the motor toward the rear of the vehicle.

5 Positioned across a restricted central portion of the housing 1 are a pair of partition members in the nature of dampers 15 and 16, pivotally mounted by means of respective shafts 15' or 16'. In the position shown, these partitions prevent direct communication of 10 air from the space 2 to the space 3. These partitions may be swung down to close the respective openings 5 and 6 in which case through passage of air is afforded from one end of the housing 1 to the other, exclusive 15 of the heater unit housing. Individual arms 17 carrying thumb screws 17' may serve to hold the partitions in adjusted position by causing the screws to bear against the adjacent wall of the housing 1.

20 The fan 21 may be of any convenient type and is positioned within a frame 25 providing a circular opening just clearing the fan blades. The frame may be flanged at 25' to bridge across the joint between the housing 25 sections 1 and 4. The flange may be bolted or otherwise rigidly secured to the walls of the housing 1. A suitable electric motor for driving the fan is shown at 21 adjustably secured in place by reason of a bar 22 engaging 30 a hollow boss 23' on a floor plate 23, the latter being secured to the vehicle body floor as by screws (not shown).

The fan housing section 4, rests upon and is secured to the floor plate 23 by reason of 35 ears 23" on the plate, adapted to receive screws (not shown) carried by the side walls of the housing section. Thus the fan and motor may be entirely uncovered for the purposes of inspection, oiling, etc., simply by 40 moving the section 4. Air is supplied to the fan through any convenient arrangement of openings, there being perforations 4' in the end wall of the section 4 and similar openings 4" in the side walls. Suitable means for controlling the fan motor may comprise any convenient arrangement of electrical conductors 45 (not shown) including a source of supply such as a battery arranged to be controlled by a switch at the instrument board of the 50 vehicle.

When the fan motor is started, air is drawn in through the openings 4' and 4" and forced 55 into the chamber 2, then deflected downwardly by the top wall of the housing section 1, shown as inclined, and by the partition member 15 into the heating unit housing 10. A depending partition plate 27 serves to divide the single opening in the floor into an inlet 60 and outlet for the heater unit housing. The plate preferably makes contact with the adjacent housing parts at its top and side edges, but is spaced from the bottom of the housing 10 to provide a generous air passage. The plate thus distributes the air uniformly over 65 the manifold of pipes, where it absorbs heat

radiated by the pipes. The air then passes upwardly through the opening 7 into the discharge chamber. Preferably both openings 6 and 7 are guarded by screens, such as 28 and 28' respectively, mainly to prevent foreign materials from being thrown through the openings into the heater housing.

70 Assuming the heat of the manifold is substantially constant, the heating effect of air delivered from the heating unit is governed largely by the speed at which the fan operates. For example, air blown past the manifold at low velocity will attain a fairly high temperature, but the heating value will be less because it will not as readily permeate the entire body 75 as will a large volume of air at higher velocity.

80 A convenient installation of the device is as shown in Fig. 1, wherein the intake end of the upper housing is directed inwardly toward the center of the vehicle, and the discharge end toward the side wall of the vehicle, designated W. The housing 1 is purposely made of such dimensions as to fit under the usual seat structure which is shown conventionally at S. The relation of the housing to the seat structure may of course be reversed, or the housing turned at right angles to the position shown, as determined by installation problems and conditions. The 85 heating unit housing 10 is preferably a box-like structure with insulated side and bottom walls and solid end plates for supporting the manifold pipes and exhaust line adapters. The side and bottom walls comprise inner 90 wall sections of sheet metal 30, outer sections of similar sheet metal 31, and an intermediate layer of heat insulating material, such as asbestos, this layer being designated 32. The end walls are preferably comparatively 95 thick metal plates 33, to which the side and bottom walls just described are attached, as by reason of marginal portions 31' of the outer layer 31 overlying the peripheral edges 100 of the plates.

105 The housing is supported by an annular frame 34 having horizontal flanges 35 adapted to be sustained by the vehicle body floor preferably by bolts (not shown) passing through the flange 35, the floor and flanges 1' on the housing 1. The plates 33 may be bolted to the depending portions of the frame as shown in Fig. 3. In order to prevent damage to the body floor by excessive heat from the manifold we provide comparatively heavy 110 insulating gaskets at 36 and 37 between the housing walls and frame 34 and between the flanges 35 and the body floor. This also reduces direct heat conductivity from the housing 10 to the housing 1 so that in warm weather the housing 1 is kept comparatively cool. The frame 34 is extended upwardly 115 past the opening in the floor and this extension is in close overlapping i. e. telescoping 120 relation to a depending skirt portion 39 of

the housing 1. The telescoping arrangement of parts 34 and 39 permits considerable variation in body floor thickness.

The manifold pipes 11 may be of any known type but are preferably short sections of tubular members provided with radiating fins to increase the effective radiation area. Such tubes are obtainable on the market as "Fin-Tubing", and comprise metal pipes having helically formed edgewise bent strips of metal 38 wound on and secured thereto as by welding. The ends of these pipes may be brazed into openings in the plates 33, or otherwise secured in such openings to afford gas tight joints. In order to incorporate these pipes into the exhaust line, we preferably use hollow adapter members, such as 40 attached as by means of flanges 41 to the plates 33, these adapters being brazed onto, or otherwise suitably secured to respective sections E and E' of the exhaust pipe. The adapters are generally conical in shape mainly to prevent back pressure at the discharge end of the manifold. Suitable means such as baffles (not shown) may be employed within the adapted members to provide uniform distribution of the exhaust gases through all the pipes. It will be noted that likelihood of the exhaust gases passing into the body of the vehicle is fairly remote by reason of the unitary character of the pipes, and the end plates 33, the only flanged connection being outside of the heater chamber, namely, the connections between the adapters 40 and the plates 33 which are sealed by gaskets 42.

With the above described arrangement heated air may be circulated through the body of the vehicle in varying volumes, depending upon the rate of operation of the fan. If desired, however, we may circulate air in the body of the vehicle without heating it, as for simply ventilating the body in warm weather. This is by reason of the movably mounted partition members 15 and 16, which as previously mentioned may be swung down to effectively close the openings 6 and 7. The air is then blown straight through the housing 1 exclusive of the heating chamber.

If desired, the device above described may be used with the partition members 15 and 16 in inclined position, thus allowing a portion of the air delivered by the fan to pass directly through the housing 1, while another portion will be shunted through the heating chamber. Thus various heating and ventilating effects may be obtained with a constant speed fan motor.

In the modified form shown in Figs. 4 and 5, a somewhat different arrangement is provided, mainly for constructional reasons, and in order to cut down the size of the apparatus above the floor. With this arrangement it is not possible to operate the device while excluding the air from the heater unit, but in lieu thereof air may be drawn from the

body and exhausted below the floor, thus securing forced ventilation of the body without heating the interior thereof.

In this form a fan unit housing is indicated at 50 communicating through a tube 51 to a heating unit housing 53. Both the chambers so formed communicate with the interior of the body to be ventilated, one through a tubular casting 55, screened as at 56, and the other, namely the heating chamber, through an adjustable register or distributor arrangement indicated generally at 56. The fan housing may be supported by a flange 57 near its upper end, which may be bolted, to a flange 58 on the fixture 55, the bolts passing through the vehicle body floor F as shown. 60 designates the fan and 61 the motor which may have any suitable support (not shown).

The fan chamber communicates with the tube 51 through a hollow conical fitting 64 in registration with the fan. This fitting has cross fins or webs 66 disposed entirely across it, and in planes parallel to the axis of the fan. The purpose of this is to enable the use of a comparatively small tube 51. We find that the fins prevent eddy currents to such an extent that the fan will deliver approximately the same volume of air through a tube in the proportions shown as could be delivered by a tube almost as large as the fan. The arrangement of the heater chamber 53 and manifold parts is similar to the embodiment shown in Fig. 2, and the similar parts are correspondingly numbered, viz. 11', 40', etc.

In this form of device, we find it desirable to space the heater slightly from the floor and suspend it as on hanger brackets 69. The top of the heater chamber has an opening formed by an upwardly extending annular flange 70 into which the lower end of a sleeve 71 telescopes. This sleeve is flanged as at 72 above the floor F for securing the sleeve to the floor. The sleeve 71 is extended as at 73 above the flange and is provided at its top edge with a dish shaped deflector, or air distributing device 75 arranged to be raised and lowered as by means of a series of straps 76 depending from the deflector into sliding engagement with the interior of the sleeve portion 73. The straps have thumb screws 78 secured thereto, which extend through slots 79 in the sleeve portion 73, by reason of which arrangement the deflector may be locked in raised or lowered position.

If desired, we may provide for evacuating the air from the body by means of the fan, thus securing forced ventilation for the body without returning the heated air to the body. The device for accomplishing this may comprise a slidable cap member 80 surmounting the heater housing and arranged to uncover a series of openings 83 in such wall, when slid to one of its positions. The member 80 may be suitably locked in either position as

by set screws (not shown). When so operating the device, the deflector is lowered onto the sleeve extension 73 to close it.

From the above description it will be seen that we have provided an air heating and circulating unit which is simple in character, of comparatively few parts, efficient and very compact. It will be further seen that the motor and fan are protected against excessive heating from the manifold, by reason of being in a separate chamber in each form shown, and it will be further seen that by the use of the device a large volume of air may be circulated through a vehicle body at sufficiently high temperature to heat the body. With regard to the second form described, the circulation of air is normally through the heater, but for summer weather the body may be simply evacuated of stale air, which is blown out through and from the heater chamber below the floor boards, fresh air being admitted to the body in any suitable known manner.

We claim:

- 25 1. In a device of the class described, air forcing means adapted to be positioned on one side of the wall of a body to be ventilated, a heating device including a housing and heating element therein adapted to be placed on the other side of said wall, and adjustable means to selectively cause the air forcing means to circulate air in the body through the heating device housing and to circulate air in the body while entirely preventing contact thereof with said heating element.
- 30 2. In an air heating and circulating apparatus for a vehicle body, an air circulating unit, including chamber forming means associated with the body floor, a fan and means for driving the fan located in said chamber, a heater unit positioned below the vehicle body floor, and selectively adjustable means for directing air from the fan through the heater unit and into the body entirely and directly into the body exclusive of the heater unit.
- 35 3. In a heating and ventilating apparatus, a housing open at each end and adapted to be positioned above a vehicle body floor, said housing being arranged to contain a power driven fan, a heater unit including a housing positioned below the body floor, means affording air communication from the fan containing portions of the first named housing into the heater unit housing and back into the body, there being a movable partition, normally preventing direct communication through the first named housing, said partition being arranged to close the communication afforded by said first named means and to, at such time, open said direct communication.
- 40 4. A motor vehicle body heating and ventilating apparatus, comprising, a housing open at each end and adapted to be positioned

above the floor of the vehicle body, a housing below the body floor adapted to contain a heating unit, a fan located in one end of said first named housing, means for driving the fan, movable partition means affording communication from the fan containing portion of the first named housing to the other end of the housing through the heater unit containing portion, said means being operable to close such communication and to open communication directly through the first named housing exclusive of the heater unit housing.

5. In combination, a vehicle body, a wall therefor having an opening therethrough, means dividing the opening and affording an air outlet at one side thereof and an air inlet at the other, air flow inducing means arranged to force air from the body through the outlet side of said opening, said means being positioned adjacent said opening, hollow means exteriorly of the body positioned adjacent and communicating with both sides of said opening, and a heating element within said hollow means.

6. In combination, a vehicle body, a horizontal floor therefor having an opening therethrough, air flow inducing means disposed adjacent said opening and arranged to force air from within the body through said opening, means forming a two part chamber below the floor, one part communicating directly with the floor opening, a heating element disposed in the other part, means providing an outlet conduit from the heating element containing chamber part to within the body and movable means arranged to close the conduit and said opening and to thereby prevent direct radiation of heat from the element to the body.

7. In combination, a vehicle body, a substantially horizontal floor therefor having a through opening, air flow inducing means positioned adjacent said opening and arranged to force air therethrough from within the body, hollow means below the floor and communicating with the opening, tubular means within said hollow means and adapted for connection to a source of heat to form a heating element, means rigid with and partially dividing the hollow means and arranged to direct air forced through said floor opening to substantially all the heat radiating surfaces of the tubular means, and means including the dividing means to conduct the heated air from said hollow means into the vehicle body.

8. In combination, a vehicle body to be heated, a wall therefor having an opening therethrough, a hollow member positioned in overlying relation to said opening on one side of the wall within the body and communicating with the opening, air flow inducing means housed by the member, a second hollow member on the opposite side of the wall

- positioned adjacent said opening and having inlet and outlet affording means both including said opening, said inlet affording means communicating with the first hollow member, and a heating element contained by 5 said second hollow member.
9. In combination, a vehicle body, a floor therefor having an opening therethrough, air flow inducing means adjacent said opening and arranged to force air from the body 10 through said opening, means forming a two part chamber below the body floor, one part in communication with the floor opening, a heating element disposed within said other part, means affording air communication 15 from one part to the other, means for conducting air, warmed by the heating element, back into the vehicle body, there being means to block both entrance and exit of air to and from the chamber through said opening and conducting means.
10. In combination, a vehicle body, a wall therefor having an opening therethrough, air flow inducing means adjacent said opening arranged to force air therethrough from 25 within the body, a hollow member on the outer side of said wall adjacent to and communicating with said opening, said member having substantially continuous side walls and a wall remote from the said body wall 30 joined thereto, a web positioned in said hollow member having one edge spaced from the remote wall of said member and having its side edges substantially abutting opposite side walls and arranged to deflect cold air forced 35 through the opening toward the remote wall of the member, a heating element opposite the space at the spaced edge of the web and within the said member, there being means to conduct heated air from the space surrounding the element, to within the body.
11. In heating and aerating apparatus, a hollow air collecting shell adapted to be positioned on one side of a wall of the body to be heated and aerated, and adjacent an opening in such wall, a second hollow shell adapted to be positioned on the opposite side of such wall adjacent such opening, an air flow inducing unit in one shell, a heating unit in the other shell, said shells having respective 45 mutually telescoping tubular parts one projecting into the opening and affording air communication between the two shells, there being flanges on each shell adapted to be forced against such body wall and thereby hold the telescoping parts in constant relation.
12. In combination, a vehicle body, a wall therefor, an opening through the wall, two 50 hollow members superposed on each other and both communicating with the wall opening, dividing means for both members extending continuously through the opening and arranged to direct air from one member out- 55 wardly to the other member and then back 60 into the first specifically mentioned member, air flow inducing means in one of the members on one side of the dividing means, a heating unit in the other member on the opposite side the dividing means, and means affording an inlet and outlet for air to and from the member housing the air flow inducing means.
13. In a device of the class described, a heater casing having a partition therein dividing the casing into two enlarged chambers, a heating element within the casing on one side of said partition, said partition being spaced edgewise from one wall of the casing to provide communication from one chamber 70 to the other, a wall of the casing opposite the heating element being inclined toward the heating element to direct air toward such element, and inlet and outlet openings in the casing positioned on opposite sides of said 75 partition.
14. In a motor vehicle, in combination, a body having a floor, a heating apparatus for the body comprising inlet and outlet openings through the floor, a casing below the floor 80 communicating with the outlet opening, air forcing means disposed in the casing arranged to draw air from the body through the outlet opening, a second casing located below the body floor, a heating element within the second 85 casing, means to conduct air from the first mentioned casing to the second mentioned casing to heat such air, and means to conduct the heated air from the second mentioned casing to the said inlet opening. 90
15. In a motor vehicle, in combination, a body having a substantially horizontal floor, a heating apparatus for the body, comprising inlet and outlet openings in the body substantially in the plane of the floor, a casing 95 located below the floor, conduit means arranged to convey air from said outlet opening to said casing, conduit means arranged to convey air from said casing to said inlet opening, a heating element contained in said 100 casing for imparting heat to air circulated through said casing, and air forcing means associated with the conduit means of one of said openings, said air forcing means comprising an electrically operated air forcing fan unit.
16. In a motor vehicle, in combination, a body having a substantially horizontal floor, a heating apparatus for the body comprising inlet and outlet openings in the body substantially in the plane of the floor, a casing 105 located below the floor, conduit means arranged to convey air from said outlet opening to said casing, conduit means arranged to convey air from said casing to the said inlet opening, a heating element contained in said 110 casing for imparting heat to air circulated through said casing, and air forcing means associated with the conduit means of one of said openings, said air forcing means 115 comprising an electrically operated air forcing fan unit.

being adapted to be controlled to vary the volume of air delivered from the casing to the body, independently of the operation of said heating element.

17. In a motor vehicle, in combination, a body having a substantially horizontal floor, a heater casing disposed below the floor, a heating element housed by said casing, an outlet opening in the floor for conveying relatively cool air from the body to the casing, there being conduit means affording definite communication from the opening to the casing, an inlet opening in the body substantially in the plane of said floor, and conduit means communicating between the casing and the inlet opening, and an electrically operated air forcing unit associated with the outlet opening and arranged to force air from the body through said conduit means and casing and back into the body, said unit being under the control of the operator of the vehicle, whereby the air volume may be regulated, as required, independently of the operation of the heating element.
18. In a motor vehicle, in combination, a body having a substantially horizontal floor, a heating apparatus for the body, comprising inlet and outlet openings in the body substantially in the plane of the floor, a casing located below the floor, conduit means arranged to convey air from said outlet opening to said casing, conduit means arranged to convey air from said casing to the inlet opening, a heating element contained in said casing for imparting heat to air circulated through said casing, and an electrically driven air forcing unit associated with the conduit means of said outlet opening, and disposed above the floor, whereby said unit is protected against direct radiation of heat from the heating element.
19. In a motor vehicle, in combination, a body having a substantially horizontal floor, heating apparatus for the body comprising an inlet opening in the body and a casing located below the floor, conduit means communicating between the casing and said opening, conduit means below the floor for conveying air to the said casing, a heating element contained in said casing for imparting heat to air circulated through said casing, and an electrically driven air forcing unit incorporated in the second mentioned conduit means and spaced a substantial distance from the said casing for blowing air through said conduit means, and casing and into the body.

In testimony whereof, we hereunto affix our signatures.

ALFRED R. LINTERN.
GEORGE D. LINTERN.
